Albert E. Powers of Lansingburgh, N.Y.

Letters Patent No. 2167 Dated Sept. 19. 1865

Design for Oil Cloths.

This schedule referred to in these Letters Patent and making part of the same.

To all whom it may concern:

Be it known that of Albert E. Powers of the town of Lansingburgh, County of Rensselaer, and State of New York have invented or produced a new and original design for Floor Oil Cloths and other fabrics and I do hereby declare that the following is a full and exact description of the same viz:

The ground of the pattern is formed by interlacing bands of color ornamented in what is known as Persian Style. Upon the centers of intersection of these bands is placed a white diamond shaped figure, likewise ornamented in Persian Style; and what is claimed as my invention, and desired to be secured by Letters Patent is the general arrangement and combination of figures producing a design, as shown by the accompanying drawings, which are hereby declared to be a part of this specification.
